United States Patent Office

Des. 178,948

Patented Oct. 16, 1956

178,948

AIRPLANE

Ralph L. Bayless, La Mesa, and Charles B. Carroll, San Diego, Calif., assignors to General Dynamics Corporation, San Diego, Calif., a corporation of California

Application March 16, 1955, Serial No. 35,061

Term of patent 14 years

(Cl. D71—1)

Figure 1 is a top plan view of the airplane shown in take-off position embodying our new design;

Figure 2 is an elevational view of the airplane taken from the cockpit side;

Figure 3 is a side elevational view of the airplane, and Figure 4 is a perspective view thereof.

We claim:

The ornamental design for an airplane, substantially as shown.
